UNITED STATES PATENT OFFICE.

RALPH H. WEST, OF CLEVELAND, OHIO.

DESIGN FOR A VEHICLE-WHEEL.

54,156.

Specification for Design.

Patented Nov. 4, 1919.

Application filed February 8, 1917. Serial No. 147,502. Term of patent 14 years.

To all whom it may concern:

Be it known that I, RALPH H. WEST, a citizen of the United States, residing at Cleveland, county of Cuyahoga, and State of Ohio, have invented a new, original, and ornamental Design for a Vehicle-Wheel, of which the following is a specification, reference being had to the accompanying drawings, forming a part thereof.

In said drawings, Figure 1 is a side view

of a wheel; Fig. 2 is a sectional view of a wheel; Fig. 3 is a sectional view of a spoke of a wheel, showing my new design.

I claim:

The ornamental design for a vehicle wheel, substantially as shown.

RALPH H. WEST.

Witnesses:

L. I. PORTER,
E. B. GILCHRIST.
